CLAIM

The ornamental design for a pump casing as shown and described herein.

DESCRIPTION

FIG. 1 is a perspective view of the pump casing of the present invention;

FIG. 2 is a front view in elevation of the pump casing of the present invention;

FIG. 3 is a rear view in elevation of the pump casing the present invention;

FIG. 4 is a side view in elevation of the pump casing the present invention;

FIG. 5 is a side view in elevation of the opposing side of the pump casing of the present invention as shown in FIG. 4;

FIG. 6 is a top view of the pump casing of the present invention;

FIG. 7 is a bottom view of the pump casing of the present invention; and,

FIG. 8 is a further perspective view of the pump casing of the present invention when fully assembled as a pump.

The broken lines shown in FIGS. 1-8 are included for the purpose of illustrating portions of the pump casing that form no part of the claimed design.

1 Claim, 4 Drawing Sheets
